[57] **CLAIM**

The ornamental design for a plug-in cartridge for video game and the like, substantially as shown and described.

DESCRIPTION

FIG. 1 is a front top perspective view of a plug-in cartridge for video game and the like showing my new design;

FIG. 2 is a bottom rear perspective view thereof, taken at a reduced scale;

FIG. 3 is a bottom rear perspective view with the cover for the contact end portion in an open position;

FIG. 4 is a bottom plan view of the cartridge;

FIG. 5 is an end elevation view with the contact end portion in a closed position; and

FIG. 6 is an end elevation with the contact end portion in an open position.
